UNITED STATES PATENT OFFICE.

MELVILLE CLARK, OF CHICAGO, ILLINOIS, ASSIGNOR TO MELVILLE CLARK PIANO COMPANY, OF CHICAGO, ILLINOIS, A CORPORATION OF ILLINOIS.

SECURING MEANS FOR STRIKER-PNEUMATICS.

1,173,252.

Specification of Letters Patent.

Patented Feb. 29, 1916.

Application filed July 15, 1914. Serial No. 851,051.

To all whom it may concern:

Be it known that I, MELVILLE CLARK, a citizen of the United States, residing at Chicago, in the county of Cook and State 5 of Illinois, have invented new and useful Improvements in Securing Means for Striker-Pneumatics, of which the following is a specification, reference being had to the accompanying drawings, forming a part 10 thereof.

The purpose of this invention is to provide in an autopneumatic piano playing mechanism means for conveniently adjusting the stroke-communicating member of 15 the striker pneumatic for accurate engagement of the part of the piano action upon which it is arranged to operate.

It consists of the elements and features of construction shown and described as indicated in the claim.

In the drawings:—Figure 1 is a fore-and-aft detail section of a portion embodying this invention of a pneumatic action and of the piano action with which it engages. Fig. 2 is an inverted plan view of the motor pneumatic and striking member and adjusting devices thereon. Fig. 3 is a detail view similar to Fig. 1 showing a modified form.

The drawings show a familiar form of pneumatic action, having motor pneumatics, 1, mounted in a plurality of levels or horizontal series upon shelves or transversely extending supporting bars, 2, and positioned 35 for engagement of the moving walls, 4, of the motor pneumatics with the stickers, 5, of the piano action. For engagement of said moving walls, 4, with the stickers, the latter have as usual a projecting stud or 40 pin, 6, and for engagement or encounter with these projecting studs or pins, the moving walls, 4, of the respective motor pneumatics are each provided with a striking finger, 7, which is one arm of a bell- 45 crank lever fulcrumed at 8 on the moving wall, 4, of the motor pneumatic, and having a depending arm, 9, which is engaged with the rear end of an adjusting rod, 10. This rod is screwed through a bearing, 11, 50 mounted on the under side and near the rear end of the moving wall, 4, and is provided with an additional bearing, 12, on the under side near the forward end of

said moving wall, 4. The end of the shaft protrudes forward of said forward bearing, 55 12, and is adapted to be rotated by a key or screw driver,—most conveniently, the latter,—for which purpose it has its end slotted at 13. It will be seen that by rotating the rod, 10, causing it to be screwed 60 one way or the other through its rear bearing, 11, the bell crank, 7—9, is rocked about its fulcrum, causing the striker finger, 7, to be raised or lowered; and in this manner said striker finger of each motor pneumatic 65 can be adjusted into accurate relation with the stud or pin, 6, on the striker which it is to operate.

If desired, in order to avoid reliance upon gravity and the resistance of the piano hammer action for holding the depending arm of the bell-crank lever against the adjusting rod, the latter may be provided with means for positively engaging said depending arm, consisting, as shown in Fig. 3, of 70 75 spheroidal faced stops, 15, 15, screwed on to the end of the rod, 10, at opposite sides of the depending arm of the lever, the rod being threaded for that purpose. Jam nuts, 16, 16, are preferably employed to prevent 80 loosening of the stops.

It is desirable to be able to adjust the motor pneumatics longitudinally of the action as a whole,—that is, of the supporting shelves, 2,—to bring the striker fingers into 85 registration with the stickers respectively of the piano action, these stickers being not spaced identically on different makes of pianos. For this purpose, the shelves, 2, are made narrower than the length of the 90 fixed wall of the motor pneumatics, and are beveled, as seen at 2^a; and upon the ends of the fixed walls of the motor pneumatics which protrude beyond the lateral edges of the shelves there are mounted blocks, 20, 95 having their edges toward the beveled edge of the shelf reciprocally beveled. These blocks are secured to the fixed walls of the motor pneumatics by screws, 21, taking into the holes of the blocks so positioned that 100 when the screws are tightened to clamp the blocks to the motor pneumatic fixed walls, the beveled edges of the blocks clamp the beveled edge of the shelf and bind the motor pneumatics firmly to the latter; but upon 105 slackening the screws, the grip of the clamp-

ing blocks, 20, is released, and the motor pneumatics may be re-positioned along the shelf as desired.

I claim:—

5 In a pneumatic action, in combination with horizontal shelves for supporting motor pneumatics, motor pneumatics mounted on said shelves extending crosswise thereof and protruding beyond the lateral edges of
10 the shelves, said edges being beveled, and clamping blocks secured to the protruding

ends of the motor pneumatics having their edges toward the shelves beveled reciprocally thereto, and screws for clamping the blocks to the motor pneumatics.

15

In testimony whereof, I have hereunto set my hand, at Chicago, Illinois, this 9th day of July, 1914.

MELVILLE CLARK.
